(57) **CLAIM**

The ornamental design for a digital audio player as shown and described.

DESCRIPTION

1. Digital audio player

1.1 : Perspective

1.2 : Perspective

1.3 : Front

1.4 : Back

1.5 : Left

1.6 : Right

1.7 : Top

1.8 : Bottom

1.9 : Enlarged

1.10 : Enlarged

1.1 is a front, right side, top perspective view of a digital audio player showing a new design; 1.2 is a back, left side, bottom perspective view thereof; 1.3 is a front elevational view thereof; 1.4 is a back elevational view thereof; 1.5 is a left-side elevational view thereof; 1.6 is a right-side elevational view thereof; 1.7 is a top plan view thereof; 1.8 is a bottom plan view thereof; 1.9 is an enlarged detail view of the knob portion in FIGS. 1.1; and 1.10 is an enlarged detail view of the knob portion in FIG. 1.6.

The broken lines in the drawings depict the portions of the digital audio player that form no part of the claimed design. The dash-dot-dash broken lines indicate cutoff boundaries for enlarged detailed portion views and form no part of the claimed design.
